CLAIM

We claim the design for a floating sink top, as shown and described.

DESCRIPTION

FIG. 1 is a top left front perspective view of the floating sink of our design, the dashed lines representing unclaimed features;

FIG. 2 is a front plan view thereof;

FIG. 3 is a left side plan view thereof, the right side plan view being a mirror view thereto;

FIG. 4 is a top plan view thereof, the dashed lines representing unclaimed features; and,

FIG. 5 is a bottom plan view thereof, the dashed lines representing unclaimed features.
